(57) **CLAIM**

The ornamental design for an electrode assembly for electrical stimulation, as shown and described.

DESCRIPTION

FIG. 1 is a front left perspective view of a first embodiment of an electrode assembly for electrical stimulation showing our new design, the electrode assembly including a pad, at least two electrodes secured to the pad, and at least one wire secured to and extending from the pad;

FIG. 2 is a top plan view of the first embodiment;

FIG. 3 is a bottom plan view of the first embodiment;

FIG. 4 is a right side view of the first embodiment;

FIG. 5 is a left side view of the first embodiment;

FIG. 6 is a rear elevation view of the first embodiment;

FIG. 7 is a front elevation view of the first embodiment;

FIG. 8 is a front left perspective view of a second embodiment of an electrode assembly for electrical stimulation showing our new design, the electrode assembly including a pad, at least three electrodes secured to the pad, and at least one wire secured to and extending from the pad;

FIG. 9 is a top plan view of the second embodiment;

FIG. 10 is a bottom plan view of the second embodiment;

FIG. 11 is a right side view of the second embodiment;

FIG. 12 is a left side view of the second embodiment;

FIG. 13 is a rear elevation view of the second embodiment; and,

FIG. 14 is a front elevation view of the second embodiment. The broken lines shown in the drawings illustrate portions of the electrode assembly for electrical stimulation that form no part of the claimed design. The wire is shown with a symbolic break in its length. The appearance of any portion of the wire between the break lines forms no part of the claimed design.
